Filed Mar. 22, 1967, Ser. No. 6,337

Term of patent 14 years

(Cl. D34—5)

FIGURE 1 is a perspective view of a golf putter head showing our new design;

FIGURE 2 is a top plan view thereof;

FIGURE 3 is a front elevational view thereof;

FIGURE 4 is a bottom plan view thereof;

FIGURE 5 is a rear elevational view thereof; and

FIGURE 6 is a side elevational view thereof.

The broken line showing of a shaft in FIGURE 1 is for illustrative purposes only. The characteristic features of our design reside in the combination of the particular club head shown and the hosel blending into the central bottom portion of the club head to form a runner, all as shown.

We claim:

The ornamental design for a golf putter head, substantially as shown and described.
